(57) **CLAIM**

The ornamental design for a tripod, as shown and described.

DESCRIPTION

FIG. 1 is a front elevational view of a tripod showing our new design;

FIG. 2 is an elevational view of the tripod similar to FIG.1 rotated by 120 degrees in a clockwise direction;

FIG. 3 is a top plan view of the tripod; and,

FIG. 4 is a bottom plan view of the tripod.

The portions of the tripod in broken lines are shown for illustrative purposes only and form no part of the claimed design.
